[57] CLAIM

The ornamental design for a copyholder, substantially
as shown and described.

DESCRIPTION

FIG. 1 is a front perspective view of a copyholder
showing my new design, the environmental structure
shown in dotted lines being for illustrative purposes
only and not a part of the claimed design;
FIG. 2 is a front elevational view thereof;
FIG. 3 is a top plan view thereof;
FIG. 4 is a rear perspective view thereof;
FIG. 5 is a front perspective view of an alternate em-
bodiment of the copyholder;
FIG. 6 is a top plan view thereof; and
FIG. 7 is a rear perspective view thereof.

FIG. 1
